J. J. HIGGINS

UNIVERSAL FOOT TREADLE

Filed June 6, 1921

FIG. 1.

FIG. 2.

INVENTOR
JOHN J. HIGGINS

BY
J. J. Higgins
ATTORNEY

UNITED STATES PATENT OFFICE.

JOHN JOSEPH HIGGINS, OF EAST ORANGE, NEW JERSEY, ASSIGNOR TO WESTINGHOUSE LAMP COMPANY, A CORPORATION OF PENNSYLVANIA.

UNIVERSAL FOOT TREADLE.

Application filed June 6, 1921. Serial No. 475,330.

To all whom it may concern:

Be it known that I, JOHN JOSEPH HIGGINS, a citizen of the United States, and a resident of East Orange, in the county of 5 Essex and State of New Jersey, have invented a new and useful Improvement in Universal Foot Treadles, of which the following is a specification.

This invention relates to foot-treadles for 10 controlling the operation of machines and, more particularly, it relates to adjustable foot-treadles designed to prevent fatigue incident to the operation thereof.

An object of the invention is to provide a 15 treadle which may be controlled by a swinging leg movement of the operator, the leg pivoting about the knee joint.

A further object is to provide a foot-treadle having a plurality of adjustments by 20 means of which the treadle may be readily and properly adjusted to fit operators of different stature.

Other objects of the invention will be apparent from the following detailed description.

Many types of treadles have been employed for controlling the operation of machines but none of them has been designed to 25 prevent fatigue occurring in the operator's leg by reason of the repeated use of the same muscles. One of the types of treadle which has found great favor because of its cheapness of manufacture and simplicity of construction, is one having the treadle pivoted and comprising a foot-rest pivotally mounted upon a support and having one of its ends either directly or indirectly connected by links or otherwise to the mechanism to be operated. In operating a treadle 30 of that design, the operator usually places her entire foot in the foot-rest, the rest being just large enough to accommodate the foot of the average person. By pressing with the ball of the foot on one portion of the 35 treadle by a pivotal movement about the ankle of the operator, the treadle is rocked about its pivot-point and the mechanism to which it is connected is then operated through suitable mechanical connections.

These rests are not adapted for adjustment, as they are fixed to the floor or to the framework of the machine and are usually designed for a person of average physique or stature. Consequently, when either a 40 person of short stature or one of unusually

large physique is placed at a machine employing a pivoted treadle, the rest is either too far away or too near which causes the operator, after using the machine but a short time, to quickly tire. When a person of 45 average physique is operating a machine controlled by a pivoted treadle, recourse is frequently had to the hospitals provided by the large corporations for massage treatment in order to relieve the operator of pain 50 caused by cramping of the muscles. One of the reasons such fatigue occurs is that the muscles employed are comparatively small in view of the amount of work required of them, as they are confined to the lower limb. 55 For instance, in rocking the foot about the ankle, when the ball of the foot is raised, the muscles along the front part of the leg, known as the anterior muscles, are employed, while, if a reverse movement is desired, the 60 muscles on the rear of the leg, known as the posterior muscles, come into play. The leverage being small in a pivoted treadle of the character indicated above, greater force 65 must be exerted, and, since the muscles used are comparatively small they become over-worked and thus readily fatigued. Or, it 70 may be that such fatigue is due to the abnormal manner in which these muscles are used. The normal pivotal action of the foot 75 about the ankle when walking is very slight, whereas in rocking the foot about the ankle when operating a foot-treadle of the pivoted variety, a much wider range of movement in the foot, and, consequently the muscles, is 80 evident. Therefore, the muscles are abnormally contracted and such contraction probably causes the ligaments tying or anchoring the muscles to the leg to become strained, 85 which obviously will soon cause the operator 90 to tire. Furthermore, when the muscles are constantly strained, an irritation is set up in their cellular structure and it may be due to this that the muscles frequently cramp.

Much, if not all of the suffering heretofore 95 encountered in the use of treadles of the old type has been prevented by use of a treadle which permits a wide range of adjustment to accommodate it to physiques varying in a great many respects, and also by providing a 100 treadle which is operated by a natural swinging movement of that part of the leg below the knee, the operator merely using 105 the knee joint as a pivot about which to swing the leg. By thus operating the 110

treadle, muscles are employed which do not readily tire, as they are of considerably greater length and size. These muscles are principally confined to the upper limb or 5 thigh and those used for swinging the lower limb forwardly are termed the anterior muscles of the thigh while those which bring the lower limb back to its initial position are termed the posterior muscles of the 10 thigh or upper limb. From the physical nature of these muscles, it is observable that, due to their size alone, less fatigue is bound to result. By reason of the employment of muscles of larger size with their larger fulcrum lengths, the same amount of force required to move the treadle is distributed 15 over a larger area of muscle, hence the energy of the muscles is taxed to a less extent. Furthermore, the swinging movement imparted to the lower limb is more nearly like that in which the leg moves while walking, therefore, the muscles will operate in a normal manner without excessive strain being thrown on any part of them.

20 25 A selected treadle embodying the foregoing advantages is illustrated in the accompanying drawings wherein

Fig. 1 is a side elevation of the improved treadle, and

30 Fig. 2 is a front elevation, a connection with a machine, shown diagrammatically, being indicated in each of the views.

The selected treadle which incorporates the desirable features of the present invention 35 preferably comprises a bracket to which a pair of pendent links are pivotally connected, the links supporting a foot-rest adjacent their lower ends. The foot-rest may be attached to the links in any suitable 40 manner and, in this instance, it is directly secured to the links, or it may be attached indirectly through a horizontal support, which latter may be adjusted vertically along the links. The foot-rest may be secured to the 45 horizontal support to provide for horizontal adjustment and to also secure it at an angle or obliquely to the support. Connections with the mechanism to be operated may be had by means of a bell-crank and a link or 50 other appropriate means.

Referring to the drawings, the treadle shown therein may be supported in any desired manner but, as illustrated, it is pendently or movably carried by a bracket 3 55 rigidly fastened to the under side of the framework 4 of a machine or mechanism 5 adapted to be operated by the treadle.

The parts of a treadle which contribute principally to prevent fatigue of the operator 60 are the foot-rest upon which the operator places or rests one or both of her feet, and the type of support used for carrying the said rest. A form of treadle which has been found to meet great favor among the 65 operators is one comprising a pair of pend-

ent links 6 and 7 pivotally supported at 8 and 9, respectively, in the bracket 3. These links are preferably maintained in spaced parallel relation by means of a horizontal bar or support 11. The linkage construction just described constitutes parallelogram linkage, that is, at any position of the links the figure defined is a parallelogram. This construction also maintains the links 6 and 7 parallel to each other but permits relative 70 movement therebetween. The bar 11 may be in the form of a fork, the shank 12 of which is secured in any desired manner, for ready removal adjacent the lower ends of the links to hold them in spaced relation. 75 A convenient way of removably attaching the support to the links is by means of a pair of pivoted latches 13 and 14 carried by the support and engaging circumferentially slotted studs 15 and 16, respectively, 80 snugly fitting a series of openings 10 in the lower ends of the links. The opposite ends of the support extend outwardly beyond the links and have two tines or prongs 17 and 18, having mounted between these tines 85 or prongs, a plate or foot-rest 19. The rest may have a cleat 20 fastened to its upper surface to engage the arch of the foot and prevent it from slipping along the rest. 90 The rest may be horizontally adjusted in the tines by securing the rest in any of the openings 21 through the instrumentality of bolts 22. The rest may be held in any angular or oblique position of adjustment by firmly 95 clamping it between the tines.

The object of providing the various adjustments is to better accommodate the foot-rest to the different physical characteristics found prevalent where a large number of operators is employed. Through the agency 100 of the adjustment provided by openings 10, the foot rest may be raised or lowered as desired and secured so that the distances between the pivotal points and the top of the foot rest will approximate the length of the 105 operators' legs below the knee joint, so that the arc through which the platform or rest moves is identical with that through which the foot would move when swung about the knee joint as a pivot or fulcrum point. 110

Furthermore, by reason of the horizontal adjustment permitted by the openings 21, especially when the operator has a long upper limb length, the platform may be adjusted away from her so as to bring the 115 lower limb into proper position, which may be approximately vertically above the platform, thus providing for greater ease in operating the treadle.

It may also be found desirable to effect 120 the horizontal adjustment in the openings 21 for other reasons. For instance, if the operator prefers, and finds it more comfortable, to sit close up to the work, the lower limbs will be positioned farther under the 125 130

table, and, in order to operate the treadle with any great degree of comfort while in such position, it is better to provide an adjustment in the treadle to permit its being shifted to a point beneath the knee of the operator than for the operator to attempt to operate it from its normal position. The horizontal adjustment permitted by the openings 21 readily takes care of any such 10 contingency.

By the provision of means for tiltably or angularly securing the foot-rest in the tines 17 and 18, the rest may be adjusted to conform to feet or leg deformities or for more 15 restful positions.

The treadle may be made of considerable width so that the operator is free to move her foot about to a position or posture most comfortable to her.

20 It is to be observed that, by reason of the rigid connection between the lower ends of the links, it is possible to maintain the links in parallelism and retain the platform or foot-rest during its movement in a series of 25 planes parallel to that in which it may be initially adjusted.

In order to transmit the motion imparted to the links, by movement of the foot treadle, to the mechanism adapted to be operated, a 30 suitable connection is made therewith which preferably comprises a plurality of articulated members. These members usually consist of a bell-crank 23 and a link 24. The bell crank has its intermediate portion 25 mounted on the pivot pin 9 of the link 7 and has one of its arms 26 extending parallel to that link and secured to it by a suitable means, such as a bolt 27. The other arm 28 of the bell-crank has a series of openings 29, in one of which may be secured the link 24. The link 24 usually has a slotted opening 31 in the end connected to the arm of the bell-crank so that a lost-motion connection may be provided. However, the lost-motion connection may be dispensed with and an ordinary pivotal connection used. But an advantage in having a lost-motion connection is that the operator may shift the 45 foot-rest in order to secure greater ease of position without disturbing the adjustment or the mechanism to be operated.

The bell-crank may have its position reversed to that shown in dotted outline 32 in Fig. 1, by reason of which an upward movement may be imparted to the arm 28 of the bell-crank and, consequently, the link 24 and mechanism secured thereto by the same forward or angular movement of the foot-rest.

50 The proportions of the different articulated members is such that a movement of approximately two inches in the foot-rest will produce a movement of about an eighth of an inch in the operating mechanism. However, the extent of movement of the 55 different parts may be readily regulated by

altering the lengths of the different members. If found desirable, the bell-crank may be shifted to the link 6 in order to secure a wider range of adjustment.

The operation of the treadle may be 70 briefly described as follows: The operator seats herself before the machine at a distance from the work which will be most convenient for her. The support 12 is next adjusted in the openings 10 to make the distance it lies 75 below the pivot points 8 and 9 approximately equal to the length of the operator's leg below the knee joint. The foot rest 19 is next adjusted horizontally in the tines 17 and 18 to position it very nearly under the knee joint, 80 at the time this adjustment is being made, the platform or rest is tilted or obliquely adjusted to a position where it feels most comfortable to the operator. With the parts thus adjusted and the operator's foot 85 or feet resting on the foot-rest 19, the operator merely swings the lower leg about the knee joint as a pivotal point to operate the mechanism. This movement is a natural and easy one, employing muscles which do 90 not readily cramp or become fatigued. The motion imparted to the foot rest by this movement, produces a swinging movement in the links 6 and 7 the rest moving through an arc having a radius approximating that 95 through which the lower ends of the links move. The bell-crank which is connected to one of the links has its free end raised or lowered, depending upon whether it occupies the dotted-line position or the full-line position of Fig. 1. After the lost motion is taken up between the link 24 and the bell-crank 23, the link is moved and the mechanism to be operated is thus controlled. The foot-rest returns automatically to its 100 initial position under the influence of its potential energy.

105 While I have illustrated the preferred embodiment of the invention, it is to be understood that many structural changes may be 110 effected therein and it is, therefore, to be understood that the invention is to be limited only by the scope of the appended claims.

What is claimed is:

115 1. A foot-treadle comprising a foot-rest, pendent link members positioned intermediate the sides of said foot-rest, a forked member for associating said foot-rest with said link members for movement through a given path and means for maintaining the 120 foot-rest in a constant given relative position with respect to said path.

125 2. A foot-treadle comprising a foot-rest, a plurality of links intermediate the sides of said foot-rest and disposed in a common plane for movably supporting said foot-rest, said links being so associated with said rest to maintain the same in a constant predetermined relative position with respect to its path of movement.

3. A foot-treadle comprising a foot-rest, a plurality of links disposed intermediate the sides of said rest, a forked member for associating said foot-rest with said link members for movement through a given path and means for adjustably securing said forked member to said links to vary the elevation of the path of travel of said foot rest.
- 10 4. A foot-treadle comprising a foot-rest, a plurality of parallel pendent links disposed in a common plane intermediate the sides of said foot-rest and attached thereto and means for adjustably securing said foot-rest to said links.
- 15 5. A foot-treadle comprising a foot-rest, a plurality of links disposed in a common plane and positioned intermediate the sides of said rest, a forked member for supporting said rest in angular relation to said link members and means for maintaining said links in parallelism by permitting relative movement therebetween during operation of said treadle.
- 20 6. A foot-treadle comprising a foot-rest, a plurality of pendent links supporting said rest for bodily swinging movement and means for vertically, horizontally and angularly adjusting said rest.
- 25 7. A foot-treadle comprising a foot-rest, a substantially horizontal support for said rest, means for horizontally adjusting said rest in said support, pendent links for carrying said support adjacent to their lower ends, said links having their lower ends free to move during operation of said treadle, means for vertically adjusting said support in said links and means connecting said links to a device adapted to be operated.
- 30 8. A foot-treadle comprising parallelogram linkage, a foot-rest carried by said linkage, means for varying the vertical position of the foot-rest in accordance with a distance equal to the maximum difference in the length of the lower leg of different operators, whereby a swinging movement may be imparted to the foot-rest by a swinging movement of the leg about the knee as 35 a pivot point and means for maintaining the foot-rest in a desired angular relation to path of movement thereof in accordance with the variation in the vertical position of the foot-rest.
- 40 9. A foot-treadle comprising a bracket, a link freely mounted to swing in said bracket, a foot-rest adjustably carried at the free end of said link, a bell-crank lever rockably mounted on the same pivotal point as 45 said link and having one of its ends secured to said link and means connecting the other end of said lever to a mechanism adapted to be operated.
- 45 10. A foot-treadle comprising a foot-rest, 50 a pair of pendent links carrying said rest, means for maintaining said links in parallelism upon movement thereof, a bracket for pendently and pivotally carrying said links in spaced relation, a bell-crank lever carried by the pivotal point of one of said links to 55 which it is pivotally secured, and means connecting the other arm of said bell-crank to a device adapted to be operated, whereby, upon swinging movement of said foot-rest, motion will be transmitted to said device.
- 60 11. A foot-treadle comprising a bracket, a pair of spaced parallel links disposed in a common plane and pendently attached to said bracket, a foot-rest carried by said links and projecting at opposite sides of said links, means for maintaining the parallel relation of said links but permitting a relative movement therebetween during the swinging action of said foot-rest and an oscillatory member associated with said links for transmitting a force.
- 65 12. A foot-treadle comprising two swingably supported members disposed in a common plane, a foot-rest associated with said members, said members being disposed in a plane intermediate the sides of said foot-rest and transverse thereto and a lever arm associated with said members to transmit a force.
- 70 13. A foot-treadle comprising a bracket, a pair of spaced parallel links disposed in a common plane pendently mounted on said bracket, a forked member for maintaining said links in parallelism during movement, a foot-rest pivoted in said forked member and means for adjustably holding said foot-rest in angular position, whereby upon application of force to said foot-rest, swinging movement is imparted to said links and 75 said rest maintained in parallel planes during such movement.
- 75 14. A foot-treadle having parallel linkage for permitting its operation by a swinging movement of a leg of an operator, a foot-rest associated with said linkage, a forked extension adapted to position said foot-rest in symmetric relation to said linkage and a lever arm associated with the treadle and adapted for oscillation by reason of the movement imparted to the treadle 80 by the operator.
- 80 15. A foot-treadle comprising a foot-rest, means for pendently supporting said rest, means for securing said rest in said means for adjustment vertically, horizontally and obliquely and means for maintaining said foot-rest in parallel planes during movement thereof.
- 85 16. A foot-treadle comprising a reciprocal member, a foot-rest, pivoted parallel members for supporting said foot-rest at the free ends of said members and a lever arm associated with said reciprocal member and having a pivot point in common with 90
- 90 95 100 105 110 115 120 125 130

a pivot point of one of said members said lever arm and one of said parallel members constituting a bell crank to actuate said reciprocable member.

5 17. In a foot-treadle operated mechanism, a universal foot-treadle comprising a swingably supported foot-rest, adjustable means for tiltably supporting said rest, means for permitting horizontal adjustment of said

rest and means, including parallelogram linkage, connecting said treadle to said mechanism, whereby, upon movement of said foot-rest, said mechanism is operated.

In testimony whereof, I have hereunto subscribed my name this 2nd day of June 15 1921.

JOHN JOSEPH HIGGINS.
